UNITED STATES PATENT OFFICE.

AMOS L. FOREMAN, OF BALTIMORE, MARYLAND.

BOTTLE WASHING, RINNING, AND STERILIZING MACHINE.

1,151,538.

Specification of Letters Patent. Patented Aug. 24, 1915.

Application filed March 3, 1910. Serial No. 547,034.

To all whom it may concern:

Be it known that I, AMOS L. FOREMAN, a citizen of the United States, residing in Baltimore, Maryland, have invented certain 5 Improvements in Bottle Washing, Rinsing, and Sterilizing Machines, of which the following is a specification.

The object of my invention is to provide a machine for effecting the thorough washing, rinsing, and sterilizing of bottles, the construction and function of the various parts of the machine being fully described hereinafter in connection with the accompanying drawings, and the various parts of 15 the machine or the combinations of parts therein which constitute the subject of my invention being specifically claimed.

In the drawings—Figure 1 is a side elevation of a machine constructed in accordance 20 with my invention, certain of the upper parts of the machine being omitted; Fig. 2 is a sectional plan view of the machine on the line *a—a*, Fig. 1; Fig. 3 is a plan view of the device whereby the bottle-carrying 25 crates are caused to move forward through the machine; Fig. 4 is a plan view of a device for supporting the crate during the time that the latter is being moved vertically; Fig. 5 is an inverted plan view of 30 the mechanism whereby rotating movement is imparted to the series of bottle-cleaning brushes; Fig. 6 is a transverse vertical section on the line *b—b*, Fig. 1; Figs. 7 and 8 are inverted plan views of the devices 35 through the medium of which the crates, with the bottles contained therein, are pushed downward; Fig. 9 is a vertical sectional view of one of the bottle-cleaning brushes and of the rotating device whereby 40 it is carried; Fig. 10 is a vertical sectional view of one of the devices employed in connection with the rinsing member of the machine; Fig. 11 is a vertical sectional view 45 of one of the devices employed in connection with the sterilizing member of the machine; Fig. 12 is a longitudinal section of part of the machine, and Fig. 13 is a vertical section of the means employed for effecting depression of the bottle-carrying crates. Figs. 7, 50 8 and 12 are on a larger scale than Figs. 1 to 6, and Figs. 9, 10, 11 and 13 are on a still larger scale.

The machine comprises a succession of

units similar to each other in general construction, the differences being only such 55 as are necessitated by the different functions to be performed by the successive units of the machine.

In the drawings, I have illustrated a machine comprising three units, one for effecting 60 the brush washing of the bottles, another for effecting the rinsing of the bottles after they have been brushed, and a third for effecting the sterilizing of the bottles 65 after they have been brushed and rinsed, but other units may be added, if desired, for instance, there may be in advance of the brush washing unit, one for treating the bottles with an alkali solution for loosening the dirt and there may be a unit beyond the 70 sterilizing unit for effecting the drying of the sterilized bottles, although, ordinarily, the heat of the bottle when it leaves the sterilizer is sufficient to cause the spontaneous drying of the same. 75

A general description of one unit will suffice for all and I will therefore describe at the outset a single unit and those co-operating parts which are alike in all of the units and will then describe those features of 80 each unit in which it differs from the others.

Each unit comprises a tank 1, 1^a or 1^b mounted upon legs 2 which may rest directly upon the floor of the room or apartment in which the machine is situated or 85 may be mounted upon and secured to a bed plate or foundation common to all of the units, or may constitute a part of said bed plate or foundation. Each tank 1, 1^a or 1^b is preferably of circular form and has 90 mounted upon the top of it a section 3 of a runway which supports the bottle-carrying crates *w* as they are being fed through the machine, this runway having an extension 4 at one end of the machine for receiving 95 the crates carrying the dirty bottles and a similar extension 4^a at the opposite end of the machine for receiving the crates carrying the bottles which have been brush-washed, rinsed and sterilized. Mounted in 100 and extending above the tank at each side of the same is a post 5, these posts serving as vertical guides for arms 6 projecting from a rectangular frame 7, the latter serving to support the bottle-carrying crate while the 105 same is being pushed down into the tank.

by the mechanism hereinafter described, each of these frames 7 being normally held in its raised position by means of counterbalance weights 9 connected to chains 10 which pass over sheaves 11 mounted upon bearings on the runway 3 and are connected to arms 12 on the frame 7, as shown in Fig. 4. Rising movement of the frame 7 is arrested when it reaches its proper position by contact of the arms 6 with a frame 13 (Fig. 12) mounted in the upper portion of the tank, and carrying brushes 14 for scrubbing the outer sides of the bottle-carrying crates as the latter descend into and 15 rise from the tank.

The bottle-carrying crate α is pushed down into the tank 1, by means of a frame 15 carried by the lower end of a piston rod 16, which has a crosshead 17 guided vertically upon the posts 5, said frame 15 having, at each end, one or more (in the present instance, two) spring-pressed plungers 19 (Fig. 13) which, as the frame 15 is depressed, contact with the upper faces of the 25 ends of the bottle crate and push said crate downward into the tank together with the frame 7 upon which the crate is resting, the use of the spring-pressed plungers serving to prevent the imparting of any shock 30 or jar to the crate and its bottles when the pusher begins to act upon the crate.

The rod 16 has a piston 20 which fits snugly in a cylinder 21 mounted upon a cross head 22 at the upper ends of the posts 5, the rod 16 passing through suitable stuffing boxes in each head of the cylinder 21 and also carrying a piston 23 contained in a cylinder 24 above and in line with the cylinder 21, as shown in Fig. 13, said cylinder 24 being open to the free inflow and egress 35 of air at its lower end but being provided with two check valves 25 and 26, the check valve 25 being located at the upper end of the cylinder and being constructed to open outwardly and the check valve 26 being located some distance below the upper end of the cylinder and being constructed to open inwardly.

Movement of the piston 20 in the cylinder 21 is caused by the action thereupon of steam, air, water or other fluid, under pressure, derived from a pipe 27 which is connected to a four-way valve 29, the latter having a branch 30 leading to the lower end 35 of the cylinder 21 and another branch 31 leading to the upper end of said cylinder, each of these branches being provided with a regulating valve 32, whereby the flow through the same can be restricted, as desired.

The four-way valve also communicates with an exhaust pipe 33 and when said valve is adjusted to the position shown in Fig. 13, the motive fluid under pressure is directed 65 through the branch pipe 30 to the lower end

of the cylinder 21, the upper end of said cylinder being open to the exhaust through the branch pipe 31, reversal in the position of the valve effecting a reversal of these conditions and opening the upper end of the cylinder 21 to the inlet of motive fluid and the lower end of said cylinder to the exhaust. Under the latter conditions, the piston is caused to descend in the cylinder 21, said descent being relatively slow at the start as it 70 is retarded by the partial vacuum produced in the upper end of the cylinder 24 by the descent of the piston 23 therein, until after said piston has passed below the lower check valve 26, which permits the air to enter the 75 cylinder 24 above the piston.

When the four-way valve 29 is adjusted to the position shown in Fig. 13, the piston 20 is caused to rise in the cylinder 21, this rise being relatively slow and being dependent 85 upon the freedom of exhaust through the regulating valve 32 and check valve 25.

The four-way valve 29 of each unit of the machine has a handle 34, all of these handles being connected by a rod 35 and the handle of the end valve being extended to form a lever 36 whereby all of the valves may be simultaneously operated and the depressor frames 15 of all of the units of the machine thereby caused to descend and ascend simultaneously. 95

The bottle-carrying crates α are fed forward over the runway 3 by means of a pusher frame 40, as shown in Fig. 3, this frame having a cross-bar 41 at its rear end 100 for engaging the rearmost crate and properly spaced lugs 42 on each side of the frame for engaging the crates in advance, the frame having a handle bar 43 whereby it may be operated. 105

Forward movement of the pusher frame 40 is effected when the supporting frame 7 and depressor frame 15 are in their elevated positions, and such movement serves to bring a bottle-carrying crate directly above 110 a supporting frame 7 of each of the tanks 1, the frame 40 being retracted when the bottle-carrying crates have been lowered into the tanks so as to be in a position to again 115 push them forward when they rise from the tanks.

In each unit of the machine the bottles are treated while in an inverted position in the crate. In that unit of the machine in which the brush washing of the bottles is 120 effected, there are as many brushes 45 as there are bottles in the crate, each of these brushes being adapted to enter one of the bottles as the crate is pushed down into the tank and there are also other brushes 46 located in rows between the rows of brushes 45 and serving to wash the outsides of the bottles. 125

Each of the brushes 45 is carried by a spindle 47 which, as shown in Fig. 9, is se- 130

cured to a short vertical shaft 49, the latter turning in a bushing 50 which is screwed into a boss on the bottom of the tank 1, a collar 51 on the shaft having a flange which fits snugly into a recess in the top of the bushing in order to aid in preventing leakage around the shaft 49.

Each brush-carrying shaft 49 has, at its lower end, a disk 52 with crank pin 53 and the crank pins of all of the disks are fitted to openings in a frame 54 which has another opening for the reception of an eccentric disk 55 (or a crank pin) on a vertical shaft 56, the latter being free to turn in bearings in the bottom of the tank 1 and in a spider 57 below said tank.

The shaft 56 is provided with a spiral toothed gear wheel 59 which meshes with a similar gear wheel 60 on a horizontal shaft 61, rotatably mounted in bearings on the spider 57 and provided, at its outer end, with a pulley 62 for receiving a driving belt. Any other desired means of rotating the shaft 56, may, however, be adopted, for instance, the same may be directly connected to a rotary engine of any suitable type.

Each of the brushes 45 consists of bristles confined to and projecting from a twisted wire or other suitable core 63 which is so disposed as to project beyond the shaft 47 on one side and thereby cause an eccentric disposition of the brush material in respect to said shaft. I have found in practice, that this disposition of the brush material provides for a more effective cleansing of the bottles than when said brush material projects uniformly on all sides of the shaft.

The brushes 46 are carried by spindles fixedly mounted upon a frame 64 which is vertically guided upon posts 65 in the tank 1 and is supported upon coiled springs 66 surrounding said posts, as shown in Fig. 12.

When, therefore, the bottle-carrying crate is pushed down into the tank the rapidly revolving brushes 45 are caused to enter the bottles and in a short time the bottles partake of a portion of the rotating movement of the brushes, whereby the stationary brushes 46 are caused to effect the washing of the outer sides of the bottles at the same time that the rotating brushes 45 are washing the inner sides of the bottles.

During the washing operation, the bottles are completely submerged, the brush washing tank being kept filled with water up to a level which will insure such submersion of the bottles.

This supply of water for the brush washing tank is derived from a pipe 70 which communicates with the tank 1 through a valved branch 71, the heating of the water in the tank 1 being effected by injecting into the same the steam from the exhaust pipe 33 from the valve 29 corresponding to said tank 1; and also by means of live steam

conveyed to the pipe 71 through a valved branch 72 of the steam pipe 27 which supplies the motive fluid for the cylinders 21.

The rinsing tank 1^b is likewise supplied with a mixture of steam and water through a branch 73 of the water pipe 70, and this tank also receives the exhaust steam from the valves 29 employed in connection with both of the tanks 1^a and 1^b, these pipes joining in a common pipe 74. The hot water is not admitted directly to the tank 1^a, however, but first enters a compartment 75 formed on the bottom of the said tank 1^a, as shown in Fig. 12, and from this compartment the hot water under pressure escapes through nozzles 76 screwed into the bottom of the tank and projecting upwardly into the same, each of these nozzles being split at the upper end, as shown in Fig. 10, and having in its lower portion openings 77 for the admission of water from the tank, these openings being located directly above the ends of a pin 78 extending across the nozzle and swerving to divide the body of hot water ascending in said nozzle so as to produce an action somewhat like that of an ejector, and cause an inflow of water from the tank into the nozzle 76, the combined volumes of water being forcibly ejected from the tops of the nozzles, so as to strike the insides of the bottles as the bottle crates are lowered into the tank, thereby causing a rapid flow of the hot water through the bottles as long as the nozzles project into the same, the water jets causing the body of water in the tank 1^a to continue in a state of ebullition when the bottles have been removed therefrom.

The sterilizing tank 1^b likewise has a compartment 79 on the bottom of the same, this compartment being supplied with a mixture of steam and water through a branch pipe 90 and discharging the same through nozzles 91 which are secured to nipples 92, Fig. 11, screwed into the base of the tank 1^b, flow through the nozzles being normally prevented by means of a valve 93 adapted to a seat at the base of the nipple and normally maintained in contact with said seat by means of a coiled spring 94 interposed between the nipple 92 and a collar 95 on the valve stem 96, as shown in Fig. 11.

The nozzle 91 is split at its upper end in the same way as the nozzle 76 and the valve stem 96 projects above the top of the nozzle, so that when the bottles are lowered into the tank 1^b there will be no flow through the nozzles until the bottoms of the bottles strike the projecting ends of the valve stems 96, whereupon the valves will be opened and there will be a flow of steam and water through the nozzles and into the bottles. This flow at first will consist of the hot water with which the nozzle was filled before the opening of the valve 93 and after

the same has been ejected there will be a flow of hot water and steam from the compartment 79, the proportions of water and steam being so regulated that the desired heat for sterilizing purposes will be maintained.

The inverted bottles are supported by the bottom wires x' of the crates, and are held in an upright position by a rack x^2 in each of the crates, and in order to straighten the 10 bottles in the crate, in case they should have assumed other than a vertical position therein, each of the depressor frames 15 is provided with downwardly projecting pins, plugs or studs 97, (Fig. 13) which, by contact with the sides of the bottles, serve to properly adjust the same in the crates, the central studs of the group being, by preference, beveled at their lower ends to aid in performance of this function, and the central studs of the group in the depressor frame 15 corresponding with the brush washing unit of the machine being provided with brush material so as to supplement the action of the brushes 46 in washing the outer 25 sides of the bottles.

The depressor frames 15 are also, by preference, provided with plugs 99 (Fig. 13) of rubber, cork, or other elastic or semi-elastic material for bearing upon the bottoms of 30 the bottles and preventing the same from coming in contact with the metal of which the frame is composed and which, if brought into forcible contact with the bottom of a bottle, might tend to fracture the same.

35 The water is prevented from rising above the desired level in each of the tanks 1, 1^a or 1^b, by draining water therefrom, either continuously and in limited volume or intermittently and in greater volume, by manipulation of a drain valve 100, with which each of the tanks is provided.

While heated water is used in each of the tanks 1, 1^a and 1^b, the temperature of the water in the different tanks varies, being 40 least in the brush-washing tank 1, and greatest in the sterilizing tank 1^b and being regulated by properly proportioning the relative volumes of steam and water admitted to said tanks, which regulation is effected by manipulation of suitable valves with which the steam and water pipes are provided. The temperature of the bottles, therefore, increases progressively as they 45 pass through the machine, consequently by the time they reach the sterilizing tank, they are free from liability to fracture by reason of any considerable difference between the temperature of the bottle and that of the mixture of steam and water admitted thereto for sterilizing purposes.

The air trapped in the inverted bottles as they are being submerged in the tanks is rapidly forced out of the same, either by the action of the brushes in the tank 1 or by the forcible jets of water, or steam and water 55 entering the bottles in the tanks 1^a and 1^b.

The crates x are the ordinary wooden crates in which the bottles are packed right side up for storage or shipment, no special containing case or crate being needed for the 60 washing of the bottles, and the crates themselves being thoroughly cleaned at the same time that the bottles are being washed.

I claim:

1. In a bottle washing machine, the combination of a series of tanks, each having bottle cleaning devices therein, a runway for bottle carrying crates extending over the series of tanks, means for lowering a crate into each tank and raising it therefrom, and a 75 crate feeding device comprising a longitudinally guided frame having rigid pushers for acting upon the crates and carrying the same forward from tank to tank.

2. In a bottle washing machine, the combination of a series of tanks, each having bottle cleaning devices therein, a runway for bottle carrying crates extending over the series of tanks, means for lowering a crate into each tank and raising it therefrom, a 80 crate feeding device comprising a longitudinally guided frame having rigid pushers for acting upon the crates and carrying the same forward from tank to tank, and means for restoring said feeding device to its retracted 95 position when the crates are lowered in the tanks.

3. In a bottle washing machine, the combination of a tank, bottle cleaning devices therein, a vertically guided supporting frame for a bottle carrying crate, and a depressor frame acting upon said crate to force it down into the tank, said depressor frame having bottle centering devices thereon which fit between the bottles in the crate. 100

4. In a bottle washing machine, the combination of a tank, means for maintaining a body of water in said tank, nozzles projecting upwardly into the tank and having openings therein, pins crossing the nozzles below said openings, and means for supplying water under pressure to the lower ends of the nozzles.

In testimony whereof, I have signed my name to this specification, in the presence of 115 two subscribing witnesses.

AMOS L. FOREMAN.
